UNITED STATES PATENT OFFICE.

HENRY JAEDIKE, OF EVERGREEN, NEW YORK.

SHOE.

1,132,096.

Specification of Letters Patent. Patented Mar. 16, 1915.

Application filed December 9, 1914. Serial No. 876,280.

To all whom it may concern:

Be it known that I, HENRY JAEDIKE, a citizen of the United States, and residing at Evergreen, Long Island, in the county of 5 Queens and State of New York, have invented certain new and useful Improvements in Shoes, of which the following is a specification, such as will enable those skilled in the art to which it appertains to 10 make and use the same.

This invention relates to shoes, boots and the like, and the object thereof is to provide means whereby the movement of the foot in a shoe, or the movement of a shoe on the 15 foot will be prevented and the rubbing of the foot by the shoe and the consequent injury to the foot by the formation of sores, callouses, and the like obviated; a further object being to provide means whereby a 20 larger shoe may be worn than would otherwise be possible without rubbing or otherwise injuring the foot.

The invention is fully disclosed in the following specification, of which the accompanying drawing forms a part, in which the 25 separate parts of my improvement are designated by suitable reference characters in each of the views, and in which:—

Figure 1 is a sectional plan view of the 30 bottom of a shoe provided with my improvement, the shoe being only indicated by dotted lines; Fig. 2 a transverse section through the heel portion of the shoe on the line 2—2 of Fig. 1, and showing the parts 35 in full lines; and, Fig. 3 a similar section on the line 3—3 of Fig. 1.

In the practice of my invention I place in the opposite side portions of the heel of the shoe plates *a* which are of the form shown 40 in Figs. 1 and 2, the outer sides thereof being convex and the inner sides concave. These plates fit between the outer body portion *b* of the shoe and the inner portion or lining *b*².

45 I also countersink in the top of the heel, or pass through the top portion of the heel, or place between the top layer of the heel and the next adjacent layer a transverse rod *c*, and the plates *a* are provided at their bottom edges with thickened heads or studs *a*² through which the opposite ends of the rod *c* pass, and said ends of said rod are provided with reverse threads and the heads *a*² of the plates *a* are provided with corresponding threads, and said heads *a*² of the plates *a* are movable radially or transversely

of the heel of the shoe in recesses *d* formed in said heel, and by turning the rod *c* the plates *a* may be drawn inwardly or forced outwardly according to the direction in 60 which said rod is turned, and said plates may thus be made to securely grasp the opposite sides of the heel and hold it and prevent the heel from moving up and down in the shoe, or the shoe from moving up 65 and down on the heel, and also prevent any lateral movement or forward movement of the heel in the shoe.

It will be understood, of course, that the 70 lining *b*² in the opposite side portions of the heel of the shoe move inwardly with the plates *a* and the rod *c* is provided in its ends with transverse recesses *c*² adapted to receive the edge of a screw driver, and said rod may thus be turned in the manner of 75 an ordinary screw, as the ends thereof project through but are flush with the sides of the heel, as clearly shown.

I also place in the front portion of the 80 shoe, or in the opposite sides thereof plates *e* similar in all respects to the plates *a* but adapted to operate on the opposite side portions of the foot across the ball thereof, and these plates are operated by a transverse rod *f*, and the details of this construction are 85 shown in Fig. 3 and are in all respects similar to that shown in Fig. 2, except that the rod *c* is placed in connection with and operates in connection with the heel *g* of the shoe while the rod *f* is placed transverse of the 90 sole *h* of the shoe.

The plates *e* are also placed between the 95 inner lining *b*² of the shoe and the outer or body portion *b* thereof, and the method of connecting the rod *f* with the plates *e* and operating said plates by means of said rod is the same as is shown in Fig. 2 and is clearly indicated at *i*.

The plates *e* may be caused to grasp the 100 sides of the foot and hold the foot against lateral or forward movement of the shoe and also prevent the shoe from lateral or forward movement on the foot, and by means of this construction herein shown and described, the object of my invention as hereinbefore set out is accomplished; and while I have shown and described the construction which I prefer, my invention is not limited to the details thereof, and changes therein and modifications thereof 105 may be made, within the scope of the appended claims, without departing from the 110

spirit of my invention or sacrificing its advantages.

Having fully described my invention, what I claim as new and desire to secure by Letters Patent, is:—

1. A shoe provided in the opposite sides of the front portion thereof and inside of the body of the shoe with laterally movable members which are adapted to grasp and hold the foot.

2. A shoe provided in the opposite sides of the heel portion thereof and inside of the body of the shoe with laterally movable side members, and means whereby said members may be moved outwardly and inwardly.

3. A shoe provided in the opposite sides thereof and in both the heel and front or body portion of the shoe and inside of the body of the shoe with laterally movable members, and means for operating said members, substantially as shown and described.

In testimony that I claim the foregoing as my invention I have signed my name in presence of the subscribing witnesses this 5th day of December 1914.

HENRY JAEDIKE.
